SHEET FEEDING APPARATUS

Leonard Baker, Hillsdale, N. J., and Leo C. Williams, Pearl River, N. Y., assignors to Dexter Folder Company, Pearl River, N. Y., a corporation of New York

Application March 4, 1941, Serial No. 381,646

23 Claims. (Cl. 271—26)

This invention relates to sheet feeders and more particularly to sheet handling devices thereof comprised by suction sheet separators and forwarders.

One object of the present invention is to provide improved vacuum operated suction sheet handling devices of the telescoping type which, while capable of acting on paper, cardboard, thin metal and other relatively light sheets, are particularly adapted for acting on thick metal, fibre board, plywood, pressed wood and other relatively heavy sheets.

Another object of the present invention is to provide a sheet feeder having improved vacuum operated suction devices of the telescoping type which are capable of separating and forwarding thick metal, fibre board, plywood, pressed wood and other relatively heavy sheets from a pile or supply thereof.

Another object of the present invention is to provide improved vacuum operated suction sheet handling devices of the telescoping type which are relatively small in size and yet capable through the provision of novel means incorporated therein of lifting thick metal, fibre board, plywood, pressed wood and other relatively heavy sheets from a pile or supply thereof.

Another object of the present invention is to substantially increase the power of a vacuum operated suction sheet handling device without an increase in the size of the piston.

Another object of the present invention is to provide an improved vacuum operated suction sheet handling device of the telescoping type wherein atmospheric pressure controlled by the sheet is applied to one side of the piston upon the lifting movement thereof and thereby increase the lifting power of the piston.

These and other objects of the present invention will appear as the following description thereof proceeds and in order to more clearly understand said invention reference may be had to the accompanying drawing which illustrates one embodiment thereof.

In said drawing:

Fig. 1 is a fragmentary vertical longitudinal sectional view of a sheet feeder embodying the present invention;

Figs. 2 and 3 are enlarged longitudinal sectional views of one of the vacuum operated telescoping suction sheet handling devices illustrated in Fig. 1, and showing certain parts thereof in the positions they occupy when a sheet is engaged and lifted from the top of the pile; and

Fig. 4 is a view similar to Figs. 2 and 3 but showing said parts in the positions they occupy after a sheet has been lifted and vacuum is broken in the device.

Referring to the drawing, wherein like reference characters designate like parts throughout the several views, 5 indicates a frame comprised at opposite sides of the feeder by front uprights 6 and rear uprights 7 connected together by side members 8. A pile board 9 and pile of metal or other sheets 10 are supported in the feeder on a pile elevator (not shown) which is of well known construction and operation and needs no detail description herein except to say that as sheets are fed off the top of the pile, the elevator and pile board 9 are intermittently raised in the usual manner to keep the top of said pile at a proper level for separation and feeding of sheets therefrom.

The sheets of pile 10 are separated one after another from the top and rear thereof by separating devices located adjacent the rear corners of the pile and actuated in opposite directions by vacuum to engage and lift the rear portion of the topmost sheet. The separating devices, indicated broadly at 11, are carried by brackets 12 which are mounted on, and slidable along, a rear cross member 13. This cross member 13 forms part of an auxiliary frame 14 which includes side members 15. The auxiliary frame 14 is pivotally mounted at opposite sides of the feeder, as at 16, on brackets 17 which are bolted or otherwise suitably secured to the side members 8. The auxiliary frame 14 is supported at the rear thereof by pins 18 secured in any suitable manner in the rear uprights 7.

Each sheet separated by the separating devices 11 is advanced from the pile by forwarding devices located adjacent the front of said pile and actuated in both directions by vacuum to engage and lift the front portion of the separated sheet. The forwarding devices, indicated broadly at 19, have swinging movement to advance the separated sheets, and for this purpose said devices are secured to arms 20 fixed on a rock shaft 21 which extends transversely of the feeder and is journaled in suitable bearings in the brackets 17. The sheet forwarding devices 19 are rocked rearwardly by a spring (not shown) and forwardly by a cam 22 fixed on a cam shaft 23 which extends transversely of the feeder and is journaled in suitable bearings in the front uprights 6. The cam shaft 23 is driven in any suitable manner by any suitable source of power, as for example, the printing press or other machine with which the feeder is associated. The cam 22 engages a roller

24 journaled on a cam strap 25 extending over the cam shaft 23 and connected with an arm 26 which is fixed on the rock shaft 21.

Each sheet separated from the pile by the sheet separating devices 11 is taken by the sheet forwarding devices 19 and delivered thereby to a conveyor comprised by a driven feed roller 21 which extends transversely of the feeder and is journaled in suitable bearings in the front uprights 6. Cooperating with the feed roller 21 are drop rollers 28 journaled on arms 29 which are fixed on a rock shaft 30. The rock shaft 30 extends transversely of the feeder and is journaled at opposite ends thereof in suitable bearings in plates 31 which are bolted or otherwise suitably secured to the front uprights 6. The drop rollers 28 are raised and lowered in the usual manner once during each cycle of operation of the feeder to receive each forwarded sheet delivered between said rollers and the feed roller 21 and thereafter assist feeding of the sheet by the feed roller toward the machine or instrumentality to be fed.

The suction sheet separating devices 11 and the suction sheet forwarding devices 19 are identical as respects their construction and sheet engaging and lifting operation and a description of one of said devices will therefore be sufficient for all of the same. These suction devices are, in accordance with the present invention, each preferably constructed and operated as follows. Referring now more particularly to Figs. 2, 3 and 4, each suction device includes a cylinder 32 which is relatively small in diameter and closed at its upper and lower ends by caps 33, 34, respectively, secured in any suitable manner in said cylinder. Slidably mounted in the lower cap 34 of the cylinder 32 is a hollow piston stem 35 which is open at both ends and projects through said cap beyond the same. Fixed on the projecting end of the hollow piston stem 35 exteriorly of the cylinder 32 is a rubber suction cup 36 provided with a duct 37 connecting said cup and said hollow stem through the lower open end of the latter.

Slidably mounted in the cylinder 32 and secured to or formed integrally with the hollow piston stem 35 at the other end thereof is a piston head 38 provided with a skirt 39. Surrounding the hollow piston stem 35 and interposed between the piston head 38 and the cap 34 is a light compression spring 40 adapted to hold said head, said stem and the suction cup 36 in their normal full line positions shown in Figs. 1 and 4 when no vacuum is created in the cylinder 32. In order to prevent the piston head 38 from becoming "air bound" at the top of the cylinder 32, a boss 41 extends slightly above the said head and is provided with slots 42 or the like.

The cylinder 32 is provided longitudinally thereof with a chamber or connection 43 the lower end of which has a port 44 for establishing communication between said chamber and the interior of said cylinder beneath the piston head 38. The upper end of the chamber 43 communicates with a port 45 which is formed in the upper cap 33 and disposed in vertical alignment with said chamber. This port 45, in turn, opens into a cylindrical bore or valve chamber 46 which is preferably formed in, and extends horizontally through, the cap 33. The cylindrical bore 46 in cap 33 is closed at one end thereof by a cover plate 47 and at its opposite end by a cover plate 48 which is pro-

vided with a relief port 49 in communication with said bore and opening outwardly to atmosphere. The cover plates 47 and 48 are secured to the cap 33 by machine screws 50 or the like. The cap 33 has also formed therein a port 51 which is spaced from the port 45 and establishes communication between the bore 46 in said cap and the interior of the cylinder 32 above the piston head 38. Connected with the cap 33 and communicating with the bore 46 therein is one end of a flexible conduit 52 the opposite end of which is connected with a vacuum pump (not shown) or other suitable source of vacuum through a suitable valve mechanism (not shown) which controls the making and breaking of vacuum in the cylinder 32 at predetermined intervals.

Fitted for reciprocation in the cylindrical bore or valve chamber 46 is a valve member 53 provided at one end thereof with a reduced portion 54, and intermediate its ends with a reduced portion 55 which forms spaced valve elements 56 and 57. The valve element 56 is provided near its periphery with a port 58 which preferably is somewhat smaller in diameter than the port 45 and extends horizontally through said valve element. This port 58 establishes communication between the flexible conduit 52 and the upper end of the cylinder 32 through the reduced portion 55 of valve member 53, the bore 46 and the port 51. A light compression spring 59, encircling the reduced portion 54 of valve member 53 and interposed between the latter and the cover plate 47, normally tends to move the valve member toward the right (Figs. 2, 3 and 4) so that the relief port 49 in cover plate 48 is normally closed by the valve element 57 and the port 45 in cap 33 is normally in communication with the flexible conduit or source of vacuum 52 through the bore 46 and the reduced portion 55 of said valve member as shown in Fig. 4 of the drawing.

Any suitable means may be provided for adjusting the size of the connection between the atmosphere and the lower end of the cylinder 32 whereby the speed of the lift of the piston head 38 may be controlled. The means particularly illustrated for accomplishing this result will now be described. Movement of the valve member 53 toward the left (Figs. 2, 3 and 4) by vacuum as hereinafter described, is limited by a stop member preferably in the form of a machine screw 60 which is threaded in the cover plate 47 and adapted to be engaged by the reduced portion 54 of said valve member. By turning the stop member 60 in opposite directions the extent of movement of the valve member 53 in the bore 46 as aforesaid may be varied so that more or less of the port 45 in cap 33 is covered or uncovered by the valve element 57 as shown in Fig. 3 of the drawing, thereby controlling the speed of upward movement of the piston head 38. The stop member 60 may be locked in adjusted positions by a lock nut 61.

The operation of the suction device which has just been described is as follows. When vacuum is created in the flexible conduit 52, and with the parts of the suction device in their normal positions shown in Fig. 4, vacuum is likewise created in the lower end of the cylinder 32 through the cylindrical bore 46, the reduced portion 55 of valve member 53, the port 45, the chamber 43 and the port 44. Vacuum so created in the lower end of the cylinder 32 and beneath the piston head 38 causes said head, the piston stem 35 and the suc-

tion cup 36 to move downwardly, compressing the spring 40, until the suction cup engages the top sheet of the pile 10 as shown in Fig. 2 of the drawing. The vacuum in the conduit 52 also draws air through the port 58 in the valve element 56, port 51, cylinder 32, hollow stem 35 and duct 37 in the suction cup 36. However, the port 58 is small enough so that this air infiltration does not reduce the vacuum pressure materially and hence sufficient vacuum pressure is created upon the lower side of the piston head 38 so that it and the suction means move downwardly, as described, against the pressure of the compression spring 40. No vacuum or substantially no vacuum is created over the top of the piston head 38 and to the left of the valve element 56 because the duct 37 in the suction cup 36 is open to atmosphere. However, when the suction cup 36 engages the top sheet of the pile, it is sealed thereby and a vacuum is then created in the suction cup so that the top sheet is held thereby. Immediately upon sealing of the suction cup 36 by the top sheet of the pile, vacuum will also be created in the upper end of the cylinder 32 and in the piston stem 35 and suction cup 36 through the bore 46, the reduced portion 55 of valve member 53, and the ports 58 and 51 in the valve element 56 and cap 53, respectively.

As shown in Fig. 3, when vacuum is created in the upper end of the cylinder 32 and in the cylindrical bore or valve chamber 46 because of the sealing of the suction cup 36 by the sheet, atmospheric air pressure through the relief port 49 acts on the right face of the valve element 51 and pushes the valve member 53 toward the left until the reduced portion 54 of said valve member engages the stop member 60. Under these conditions, the valve element 57 is moved away from the relief port 49 in cover plate 48 and beyond the port 45 in cap 33 thus breaking the connection between the source of vacuum 52 and the lower end of the cylinder 32 and at the same time establishing communication between said ports and opening the lower end of the cylinder to atmosphere through the port 44, the chamber 43, the port 45, the bore 46 and the relief port 49. Even though the valve member 53 has moved and opened atmospheric pressure to the lower side of the piston head 38, the vacuum connection between conduit 52 and the top of the cylinder 32 remains connected to apply vacuum therein. A condition exists then in which the top of the piston head 38 has vacuum applied thereto and air pressure is applied to the piston area surrounding the piston stem 35 upon the underside thereof by virtue of the atmospheric connection through the relief port 49. Since atmospheric pressure already exists upon the area of the piston stem 35 exterior of the cylinder 32 and is now applied also to the area upon the underside of the piston head 38 within the cylinder, the effective area upon which atmospheric pressure is applied is now equal to the piston area in the upper end of the cylinder upon which vacuum is applied. The power in the return stroke is also augmented somewhat by the compression spring 40. Heretofore, the power in the return stroke was represented by the atmospheric pressure on the piston stem alone, augmented, of course, by the compression spring, because vacuum was retained within the lower portion of the cylinder or under the piston head. The return power of the piston head 38 has been increased, therefore, by the difference between atmospheric pressure and vacuum pressure applied upon the underside of the

piston head over that portion of the piston area around the piston stem 35.

When vacuum has been created in the upper end of the cylinder 32 as hereinbefore described, the piston head 38, the piston stem 35, and the suction cup 36 are raised and the top sheet which is held to the suction cup by vacuum is lifted from the pile 10, as shown in dotted lines in Fig. 3, which lift is aided by strength of the spring 40. 10 The sheet handling device will function under the vacuum and atmospheric pressure applied to the piston head 38 regardless of the spring 40 which assures the piston head remaining at its up position when no vacuum is created in the cylinder 32. Vacuum is broken in the flexible conduit 52 to release the lifted separated and/or forwarded sheet from the suction cup 36 whereupon the spring 59 in the valve chamber or cylindrical bore 46 acts through expansion thereof to return the 15 valve member 53 to its original position shown in Fig. 4 so that the suction device can be again operated by vacuum, as described, during the next cycle of operation of the feeder.

The speed of upward movement of the piston head 38 as hereinbefore described, is controlled by the size of the opening for admitting air into the lower end of the cylinder 32 through the port 45 when communication is established between said port and the relief port 49 through movement of 20 the valve member 53. Any suitable means may be utilized for controlling the size of the connection between atmosphere and the lower end of the cylinder 32 and hence the speed of lift of the piston head 38. In the construction illustrated, 25 the port 45 may be completely uncovered by the valve element 57 in which case the piston head 38 will move upwardly at maximum speed, and when the port 45 is more or less covered by the valve element 57 the speed of upward movement 30 of the piston head 38 will be accordingly slower. The speed at which the piston head 38 is to operate is governed by the weight and condition of the sheet material to be lifted by the suction cup 36, and may be varied, as desired, to suit various 35 conditions by loosening the lock nut 61 and adjusting the stop member 60 toward or away from the valve member 53, thereby varying the extent of movement of said valve member in the cylindrical bore 46 so that more or less of the port 45 is covered or uncovered by the valve element 57.

The valve means 53 described normally connects the flexible conduit 52, which is adapted to be connected to a source of vacuum, with the lower end of the cylinder 32. When vacuum is 40 created in the upper end of the cylinder 32, in the suction means 35, 36 and in a vacuum chamber at the left of the valve element 56 by a sheet sealing the suction means, the valve means 53 is then operated to the left (Fig. 3) to disconnect the lower end of the cylinder from the source of vacuum 52 and connect the same with atmosphere or atmospheric pressure through the relief port 49. The valve means 53 is retained in operated position so long as vacuum exists in the 45 suction means 35, 36. When vacuum is broken or disconnected at the desired time to release the sheet from the suction cup 36, the valve means 53 is restored to its normal position in any suitable fashion, such as by the spring 59, and the device is ready for a second cycle of operation. Although the valve element 57 performs the double function described above, it is clear that other means may be provided to perform these two 50 functions.

The sheet handling device described herein op-

erates by applying differential pneumatic pressures to the opposite sides of the piston head 38. For example, the piston head 38 is moved downwardly by creating a higher pneumatic pressure upon the top thereof under the control of valve means connected with the inlet conduit 52. When the suction means or cup 36 is sealed by a sheet, the vacuum created therein operates the valve means 53 in the cap 33 to create or secure a higher pneumatic pressure in the lower end of the cylinder 32, whereupon the piston head 38 moves upwardly to raise the suction means and the sheet carried thereby.

The head 33 with its valve means 53 constitutes a new article of manufacture which can be mounted upon an existing cylinder and piston type suction means to convert the same into a more powerful sheet handling device, as described herein. Because of the increased power of the piston or motor described herein, thick metal, fiberboard, plywood, pressed wood and other relatively heavy sheets can be lifted from a pile or supply thereof.

The present description and accompany drawing set forth with more or less particularity one embodiment of the present invention, but it is to be expressly understood that said invention is not limited to said embodiment or otherwise than by the terms of the appended claims.

What we claim is:

1. In a sheet handling device of the type having suction means which is reciprocated by a piston operating in a cylinder which is adapted to be connected with a source of differential pneumatic pressures to reciprocate the suction means to engage and lift a sheet: the improvement comprising means controlled by the sheet sealing the suction means and actuated by the vacuum created therein for applying a differential pneumatic pressure in the lower end of the cylinder as compared to the pneumatic pressure in the upper end of the cylinder whereupon lifting of said suction means and the sheet engaged thereby is effected.

2. In a sheet handling device of the type having a cylinder and piston type suction means in said cylinder which is vacuum reciprocated to engage and lift a sheet: the improvement comprising means controlled by the sheet sealing the suction means for opening the lower end of the cylinder to atmosphere whereupon lifting of said suction means and the sheet engaged thereby is effected.

3. In a sheet handling device of the type having a cylinder and piston type suction means in said cylinder which is vacuum reciprocated to engage and lift a sheet: the improvement comprising vacuum actuated means controlled by the sheet sealing the suction means for opening the lower end of the cylinder to atmosphere whereupon lifting of said suction means and the sheet engaged thereby is effected.

4. In a sheet handling device of the type having a cylinder and piston type suction means in said cylinder which is vacuum reciprocated to engage and lift a sheet: the improvement comprising means controlled by the sheet sealing the suction means for opening the lower end of the cylinder to atmosphere whereupon lifting of the suction means and the sheet engaged thereby is effected, said means also controlling the speed of upward movement of the suction means.

5. In a sheet handling device of the type having a cylinder, a piston reciprocal therein, a piston stem connected with the piston and suction

means carried by the piston stem, the piston being vacuum reciprocated to cause the suction means to engage and lift a sheet: the improvement comprising means operated when the suction means engages the sheet for closing the connection between the vacuum supply and the lower end of the cylinder and opening the same to atmosphere and remaining in operated position so long as vacuum is supplied to the device.

10 6. In a sheet handling device of the type having a cylinder and piston type suction means in said cylinder which is vacuum reciprocated to engage and lift a sheet: the improvement comprising means controlled by the sheet sealing the suction means for closing the connection between the vacuum supply and the lower end of the cylinder and opening the same to atmosphere and remaining in operated position so long as vacuum is supplied to the device.

15 7. In a sheet handling device of the type having a cylinder and piston type suction means in said cylinder which is vacuum reciprocated to engage and lift a sheet: the improvement comprising means controlled by the sheet sealing the suction means for closing the connection between the vacuum supply and the lower end of the cylinder and opening the latter to atmosphere whereupon lifting of said suction means and the sheet engaged thereby is effected.

20 8. In a sheet handling device of the type having a cylinder and piston type suction means in said cylinder which is vacuum reciprocated to engage and lift a sheet: the improvement comprising means actuated by the vacuum created when the sheet seals the suction means for closing the connection between the vacuum supply and the lower end of the cylinder and opening the latter to atmosphere whereupon lifting of said suction means and the sheet engaged thereby is effected.

25 9. In a sheet handling device of the type having a cylinder and piston type suction means in said cylinder which is vacuum reciprocated to engage and lift a sheet: the improvement comprising means controlled by the sheet sealing the suction means for closing the connection between the vacuum supply and the lower end of the cylinder and opening the latter to atmosphere whereupon lifting of the suction means and the sheet engaged thereby is effected, said means also controlling the speed of upward movement of the suction means.

30 10. In a sheet handling device of the type having a cylinder and piston type suction means in said cylinder which is vacuum reciprocated to engage and lift a sheet: the improvement comprising means actuated by the vacuum created in the cylinder when a sheet seals the suction means for closing the connection between the vacuum supply and the lower end of the cylinder and opening the latter to atmosphere and for controlling the speed of upward movement of said suction means whereupon lifting of the latter and the sheet engaged thereby is effected and at a desired speed.

35 11. In a sheet handling device of the type having a cylinder and piston type suction means in said cylinder which is vacuum reciprocated to engage and lift a sheet: the improvement comprising a valve controlled by the sheet sealing the suction means and movable in one direction for closing the connection between the vacuum supply and the lower end of the cylinder and opening the latter to atmosphere whereupon the piston lifts said suction means and the sheet

engaged thereby; and means for moving said valve in the opposite direction to normally close the cylinder to atmosphere and enable operation of said suction means.

12. In a sheet handling device adapted to engage and move a sheet and having a cylinder, a piston reciprocal therein, a piston stem, suction means upon the end of the piston stem and connected with one end of the cylinder, a restricted connection between the aforesaid end of the cylinder and a vacuum inlet port adapted to be connected with a source of vacuum which latter is connected to and disconnected from the device at desired intervals, and a second connection between the other end of the cylinder and the vacuum inlet port aforesaid: the improvement comprising valve means in the second connection and controlled by the vacuum created in the suction means and the end of the cylinder connected therewith when a sheet seals the suction means for disconnecting the second connection from the vacuum port and opening said other end of the cylinder to atmosphere, said valve means returning to its normal position upon release of the vacuum.

13. In a sheet handling device adapted to engage and move a sheet and having a cylinder, a piston reciprocal therein, a piston stem, suction means upon the end of the piston stem and connected with the upper end of the cylinder, a restricted connection between the upper end of the cylinder and a vacuum inlet port adapted to be connected with a source of vacuum which latter is connected to and disconnected from the device at desired intervals, and a second connection between the lower end of the cylinder and the source of vacuum: the improvement comprising valve means in the second connection and controlled by the vacuum created in the suction means and upper end of the cylinder when a sheet seals the suction means for disconnecting the second connection from the vacuum source and opening the lower end of the cylinder to atmosphere; and means to restore said valve means to its normal position upon release of the vacuum.

14. In a sheet handling device of the type having a cylinder and piston type suction means in said cylinder which is vacuum reciprocated to engage and lift a sheet: the improvement comprising a valve controlled by the sheet sealing the suction means and movable in one direction when vacuum is created upon one side thereof for closing the connection between the vacuum supply and the lower end of the cylinder and opening the latter to atmosphere whereupon the piston lifts said suction means and the sheet engaged thereby; and a spring for moving said valve in the opposite direction upon release of vacuum to normally close the cylinder to atmosphere and enable another operation of said suction means.

15. In a sheet handling device of the type having a cylinder and piston type suction means in said cylinder which is vacuum reciprocated to engage and lift a sheet: the improvement comprising a cap on the upper end of the cylinder having a relief port therein opening outwardly to atmosphere through one side thereof and two spaced ports for establishing communication between a source of vacuum and the upper and lower ends of said cylinder respectively; and a ported valve in said cap normally closing the relief port therein and enabling creation of vacuum in the cylinder through said spaced ports,

said valve being actuated by vacuum upon sealing of the suction means by the sheet to close the connection between the source of vacuum and the lower end of the cylinder and to open the relief port and connect the latter with one of the spaced ports whereby the lower end of the cylinder is opened to atmosphere whereupon lifting of the suction means and the sheet engaged thereby takes place.

16. In a sheet handling device of the type having a cylinder and piston type suction means in said cylinder which is vacuum reciprocated to engage and lift a sheet: the improvement comprising a cap on the upper end of the cylinder having a relief port therein opening outwardly to atmosphere through one side thereof and two spaced ports for establishing communication between a source of vacuum and the upper and lower ends of said cylinder respectively; a ported valve in said cap normally closing the relief port therein and enabling creation of vacuum in the cylinder through said spaced ports, said valve being actuated in one direction by vacuum upon sealing of the suction means by the sheet to close the connection between the source of vacuum and the lower end of the cylinder and to open the relief port and connect the latter with one of the spaced ports whereby the lower end of the cylinder is opened to atmosphere whereupon lifting of the suction means and the sheet engaged thereby takes place; and a spring for moving the valve in the opposite direction to close the relief port and enable operation of the suction means.

17. In a sheet handling device of the type having a cylinder and piston type suction means in said cylinder which is vacuum reciprocated to engage and lift a sheet: the improvement comprising a cap on the upper end of the cylinder having a relief port therein opening outwardly to atmosphere through one side thereof and two spaced ports for establishing communication between a source of vacuum and the upper and lower ends of said cylinder respectively; a ported valve in said cap normally closing the relief port therein and enabling creation of vacuum in the cylinder through said spaced ports, said valve being actuated by vacuum upon sealing of the suction means by the sheet away from the relief port and beyond one of the spaced ports to connect said ports and open the lower end of the cylinder to atmosphere whereupon lifting of the suction means and the sheet engaged thereby is effected; and an adjustable stop member for varying the movement of the valve and opening of the cylinder to atmosphere to control the speed of upward movement of the suction means.

18. In a sheet handling device of the type having a cylinder and piston type suction means in said cylinder which is vacuum reciprocated to engage and lift a sheet: the improvement comprising a cap on the upper end of the cylinder having a relief port therein opening outwardly to atmosphere through one side thereof and two spaced ports for establishing communication between a source of vacuum and the upper and lower ends of said cylinder respectively; a ported valve in said cap normally closing the relief port therein and enabling creation of vacuum in the cylinder through said spaced ports, said valve being actuated in one direction by vacuum upon closing of the suction means by the sheet away from the relief port and beyond one of the spaced ports to connect said ports and open the lower end of the cylinder to atmosphere whereupon lifting of the suction means and the

sheet engaged thereby is effected; an adjustable stop member for varying the movement of the valve and opening of the cylinder to atmosphere to control the speed of upward movement of the suction means; and a spring for moving the valve in the opposite direction to close the relief port and enable operation of the suction means.

19. A valve means for connection with a sheet handling device adapted to engage and move a sheet and having a cylinder, a piston reciprocal therein, and suction means carried by the piston comprising a valve housing having a vacuum inlet port, an open port adapted to be connected to one end of the cylinder, and a relief port opening to atmosphere; a restricted connection extending from the vacuum inlet port and adapted to be connected with the other end of the cylinder; and valve means in the housing normally connecting the vacuum inlet port with the open port, the valve means being operable to disconnect the vacuum inlet port from the open port and connect the open port with the relief port when vacuum is created in the suction means when a sheet seals the same, said valve means returning to its normal position upon release of the vacuum.

20. A valve means for connection with a sheet handling device adapted to engage and move a sheet and having a cylinder, a piston reciprocal therein, and suction means carried by the piston comprising a valve housing having a vacuum inlet port, an open port adapted to be connected to one end of the cylinder, a second port adapted to be connected with the other end of the cylinder, and a relief port opening to atmosphere; and valve means in the housing normally connecting the vacuum inlet port with the open port and operable to disconnect the same and connect the open port with the relief port when vacuum is created in the suction means upon a sheet sealing the same, the valve means having a restricted

port connecting the vacuum inlet port with the second port, said valve means returning to its normal position upon release of the vacuum.

21. A suction head in a transfer mechanism of the class described, having a vacuum cup adapted to be moved into engagement with articles to be lifted serially, a fluid pressure device to raise and lower said suction head with and without the load, and means acting to govern the lifting operation under control of said vacuum cup, whereby said vacuum cup is adapted to accommodate itself to engagement with articles of different dimensions, and each lifting operation supervenes only upon completion of a vacuum sealed joint between said cup and the load adequate to enable said cup to sustain the load.

22. In a transfer mechanism having a fluid pressure cylinder provided with a piston and spaces above and below said piston adapted to be connected through suitable ducts with a source of suction; and a pneumatic automatic valve mounted movably in a valve chamber associated structurally with said cylinder, and adapted to move in a pneumatic control circuit for regulating connections between said ducts and the cylinder spaces, said valve being movable to a position in which it shuts off suction from the space below said piston while maintaining above said piston adequate suction to hold the same at an elevated position; and a plunger, suction head and load sustained by said piston.

23. A cylinder with a pneumatic automatic control valve having the features claimed in claim 22 wherein said valve is adapted to cause the admission of atmospheric pressure in the space below said piston, thereby to aid in holding the load in an upper position.
